(57) **CLAIM**

I claim the ornamental design for a wireless hand-held vacuum cleaner, as shown and described.

DESCRIPTION

FIG. 1 is a perspective view of a wireless hand-held vacuum cleaner showing my new design;
FIG. 2 is a right-side view thereof;
FIG. 3 is a left-side view thereof;
FIG. 4 is a top view thereof;
FIG. 5 is a bottom view thereof;
FIG. 6 is a front view thereof; and,
FIG. 7 is a back view thereof.
